CLAIM

The ornamental design for a gun trigger, as shown.

DESCRIPTION

FIG. 1 is a perspective view of the gun trigger of the present invention;

FIG. 2 is a left-side view of the gun trigger of the present invention;

FIG. 3 is a front view of the gun trigger of the present invention;

FIG. 4 is a right-side view of the gun trigger of the present invention;

FIG. 5 is a rear view of the gun trigger of the present invention;

FIG. 6 is a top view of the gun trigger of the present invention; and,

FIG. 7 is a bottom view of the gun trigger of the present invention.

The broken lines in the Figures are for illustrative purposes only and form no part of the claimed design.
